UNITED STATES PATENT OFFICE.

GEORGE ALONZO LEVY, OF EAST ST. LOUIS, ILLINOIS.

ELECTRIC SIGN.

Application filed February 6, 1928. Serial No. 252,321.

This invention aims to provide a novel form of illuminated sign, so constructed that one part of the sign may be detached readily and replaced, thereby rendering it unnecessary to throw away the entire sign, when a part of the sign, only, needs changing.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

Figure 1 shows in perspective, a device constructed in accordance with the invention;

Figure 2 is a longitudinal section;

Figure 3 is a cross section on the line 3—3 of Figure 2;

Figure 4 is a plan of the supplemental member;

Figure 5 is an end elevation of the supplemental member;

Figure 6 is a longitudinal section of the supplemental member; and

Figure 7 is a cross section on the line 7—7 of Figure 6.

In carrying out the invention there is provided a box-like main member 1 which may be supported in any desired way, the main member 1 being shown as supplied with end hangers 2 pivotally mounted on a bracket rod 3. Panels 4 are mounted in the ends of the main box-like member 1, and one of the ends of the member 1 may be in the form of a door 5 which is hingedly mounted as shown at 6, to give access to the interior of the main member. The part 1 has a bottom panel 7 and side panels 8. The panels 8, 7, and 4, are so constructed that light can pass through them, and, ordinarily, the aforesaid panels are made of translucent material, such as glass, that is frosted or painted.

The panels 8 and 4, and sometimes the panel 7, are inscribed with advertising material (not shown) relating to some standard product. The merchant selling the product generally likes to have his name appear on the sign, and if the merchant's name is placed on

one of the panels, along with the lettering advertising product, the last-mentioned lettering is up-set, or has to be specially painted, since there is no certainty how many letters there will be in the name of the merchant, or where or how he will insist upon having his name placed on the sign. The foregoing being understood, it may be stated that heretofore it has been somewhat difficult to turn out a standard form of sign with a fixed lettering, and still have the name of the merchant: and one object of this invention, stated broadly, is to provide a sign which will remedy the difficulty above mentioned.

With the above and other objects in view, a pair of retainers 9, such as eyes, are mounted in the bottom 10 of the box-like main member 1. In the retainers 9, a support 11, in the form of a rod, is pivotally received, the support or rod 11 extending through a supplemental sign member 12, which generally, is in the form of a light metal box of triangular cross section, and symmetrical in cross section, so that the supplemental sign member 12 will not hang in an unsightly position. The support or rod 11 is located in the upper angle of the supplemental sign member 12, as disclosed in Figure 7, and projects through the end walls of the supplemental sign member, as disclosed in Figure 6 of the drawings. A nut 14 is preferably threaded on one end of the rod 11, and there is a head 15 on the opposite end of the rod 11, the head 15 sometimes being in the form of a simple right angle hook. The rod 11 may be thrust endwise through the eyes and through the supplemental sign member 12, and when the nut 14 is mounted in place, the supplemental sign member 12 will be supported pivotally below the bottom panel 7 of the main sign member 1 in such a position that the name 16 of the merchant will be illuminated, the name, or any other suitable inscription, being placed upon the downwardly diverging side walls of the supplemental sign member 12. Any preferred means may be employed for illuminating the box-like member 1. In the present instance, but not of necessity, several electric lights 17 are located within the main member 1, on the top thereof.

It will be understood readily that the panels 8 and 4, and perhaps the panel 7 of the box-like main member 1, may carry any standard lettering, which need not be changed, regardless of the proprietorship of

the store, the name of the proprietor being inscribed on the supplemental sign member 12, as shown at 16. The lettering on the main member 1 of the sign can remain unchanged, 5 regardless of the name of the proprietor of the store, and if the store changes hands, the main member 1 can remain unaltered, the supplemental sign member 12, alone being changed.

10. What is claimed is:—

1. In a device of the class described, a box-like main member, a source of light within the main member, the bottom of the main member being so constructed that light 15 from said source can pass through the bottom, a supplemental member located below the main member, and having sloping sides defining an angle, the sides being illuminated from said source through the bottom of the 20 main member, and a rod detachably inserted through the supplemental member and lodged in the said angle thereof, the main member being provided on its bottom with

suspension elements through which the rod passes.

2. In a device of the class described, a box-like main member provided with panels through which light may pass, one panel being an upright panel, and the other panel being a bottom panel, a source of light within the main member, the bottom panel being shorter than the bottom of the main member, thereby to leave spaces at the ends of the bottom of the main member, a supplemental member of such dimensions that it may be illuminated throughout its entire length through the bottom panel, the supplemental member having downwardly and laterally sloping sides located directly below the bottom panel, and means for suspending the supplemental member removably from spaces at the ends of the bottom of the main member.

In testimony that I claim the forgoing as my own, I have hereto affixed my signature.

GEORGE ALONZO LEVY.
